[57] CLAIM

The ornamental design for a heat retrieval unit for installation into a flue duct, as shown.

DESCRIPTION

FIG. 1 is a perspective view of a heat retrieval unit for installation into a flue duct, showing my new design;
FIG. 2 is a top plan view thereof;
FIG. 3 is a view taken from one end thereof;
FIG. 4 is a view taken from the front of the unit;
FIG. 5 is an end view taken from the end of the unit opposite to that of FIG. 3;
FIG. 6 is a rear elevation thereof; and,
FIG. 7 is a bottom plan view thereof.

FIG. 1

FIG. 6

FIG. 7
